CLAIM

The ornamental design for a label cartridge, as shown and described.

DESCRIPTION

FIG. 1 is a top, front and left side perspective view of a label cartridge showing our new design;

FIG. 2 is a rear and left side perspective view thereof;

FIG. 3 is a bottom, rear and left side perspective view thereof;

FIG. 4 is a top, front and right side perspective view thereof;

FIG. 5 is a top, rear and right side perspective view thereof;

FIG. 6 is a front elevational view thereof;

FIG. 7 is a rear elevational view thereof;

FIG. 8 is a left side view thereof;

FIG. 9 is a right side view thereof;

FIG. 10 is a top plan view thereof; and,

FIG. 11 is a bottom plan view thereof.

The broken lines immediately adjacent to the shaded areas depict the bounds of the claimed design, while all other broken lines are directed to environment. The broken lines form no part of the claimed design.
